(57) **CLAIM**

The ornamental design for a pan lid rack, as shown and described.

DESCRIPTION

FIG. 1 is a perspective view of the pan lid rack showing my new design.

FIG. 2 is a front view thereof.

FIG. 3 is a back view thereof.

FIG. 4 is a top view thereof.

FIG. 5 is bottom side view thereof.

FIG. 6 is a side view thereof; and,

FIG. 7 is another side view thereof.

The broken lines in the drawings illustrate portions of the pan lid rack which form no part of the claimed design.
